UNITED STATES PATENT OFFICE

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

CHAIN GUARD FOR NARROW-WARE LOOMS

Application filed September 12, 1929. Serial No. 392,225.

This invention relates to improvements in chain guards for the shuttle motions of narrow ware looms and it is the general object of the invention to provide a guard so constructed as to permit the use of varying lengths of lays and also to accommodate lays of different heights.

In certain types of narrow ware looms the rack rod which moves the shuttle actuating pinions is driven by a chain, and it is desirable to protect the weaver at the points where the chain meets its sprockets. Depending upon the length of the shuttle employed the lay will extend more or less beyond the loomside and it is an important object of my present invention to provide a telescoping guard which is extensible to provide for varying amounts of overhang of the lay.

Under some conditions it is desirable to raise or lower the lay depending upon the character of the cloth being woven, the lower sprocket for the chain remaining in fixed position, and it is a still further object of my present invention to provide for these adjustments by employing an extensible guard.

With these and other objects in view which will appear as the description proceeds, my invention resides in the combination and arrangement of parts hereinafter described and set forth in the claims.

In the accompanying drawings wherein a convenient embodiment of my invention is set forth,

Fig. 1 is a front elevation of one end of a loom having my invention applied thereto, certain parts being in section,

Fig. 2 is a vertical section on line 2—2 of Fig. 1 looking in the direction of the arrows,

Fig. 3 is a vertical section on line 3—3 of Fig. 2, the chain and sprockets therefore being indicated in dot and dash lines,

Fig. 4 is an enlarged detail end elevation looking in the direction of arrow 4, Fig. 1,

Fig. 5 is a horizontal section on an enlarged scale on line 5—5 of Fig. 3,

Fig. 6 is an end elevation looking in the direction of arrow 6, Fig. 1 showing the

manner of supporting the lower end of the lay sword, and

Fig. 7 is a detail top plan view taken in the direction of arrow 7, Fig. 1.

Referring to Fig. 1, I have shown the loomside 10 and a lay 11 which is mounted on swords one of which is indicated at 12. The lay sword has a lug 13 as shown in Fig. 6 through which is vertically threaded a stop bolt 14. The head of the latter engages the top of a foot 15 which is mounted on a hollow rocker shaft 16. Bolts 17 passing through slots 18 hold the sword 12 to the foot 15 and by loosening the bolt 17 and varying the position of the bolt 14 the vertical location of the lay may be varied. The rocker shaft 16 moves in a bearing 19 which is fixed to the loom frame.

A rack 20 is slidable longitudinally in a slot 21 in the upper surface of the lay, and meshes with pinions 22 which operate through devices not shown to cause reciprocation of the shuttles not shown. A chain 23 is attached to the rack and passes around a sprocket 24 mounted for rotation on a stud 25 fixed with respect to the lay. The chain extends downwardly and around a sprocket 26 which moves freely around a fixed stud 27. The chain passes through the hollow shaft 16 and is connected to an actuating rod 28. The stud 27 is carried by a forked bearing member 29 which is held in adjusted angular and longitudinal position on the hollow shaft by a clamp nut 30.

In similar manner the stud 25 is held by 85 a bracket 31 which is forked and has a foot 32 bolted to a metallic section 33 of the lay 11. The bracket can assume different positions transversely of the lay.

During operation of the loom the lay moves 90 back and forth around the axis of the shaft 16 as a pivot by a mechanism not shown, and the rack bar 20 reciprocates, moving the shuttles first in one direction through the shed of the web and then in the opposite 95 direction. It will be understood that the structure shown in Fig. 1 is duplicated at the other end of the loom. The matter thus far described is of common construction, being substantially the same as that set forth 100

in my prior Patent No. 1,462,549 to which reference may be had for a more complete understanding of the shuttle motion. For the purposes of the present description it is sufficient, it is believed, to set forth one 5 sprocket on the stud 27, although in practice I may employ more than one.

My present invention aims to provide a 10 guard or protector for the chain which operates the shuttle rack, and in carrying my invention into effect I secure a small stand 40 to the metallic section 33 of the lay by means of a bolt 41 which extends through a slot 42 lying transversely of the lay. A pivot pin 43 carried by the stand 40 passes through the 15 side plate 44 of an upper shield member 45 which is substantially U-shaped in horizontal cross section, as shown in Fig. 5. The member 45 is, therefore, pivotally mounted with respect to the lay and can swing to assume 20 any one of a number of positions under the lay.

The lower part or member of the guard is formed of a pair of substantially similar elements 46 and 47 which, as viewed in Fig. 2, 25 lie respectively to the right and left of the chain sprocket 26. Each member has at the upturned end thereof an ear 48 through which passes a clamping bolt 49 held in position by a nut 50. As shown particularly in 30 Fig. 5 each element is provided with a substantially vertical wall 51 and a side plate 52 which has near the upper end thereof a short retaining rib 53. The distance between the 35 wall 51 and the rib 53 is substantially the same as the width of one of the walls 44 of the shield member 45. The elements 46 and 47 are made of opposite hand so that when assembled with their upper ends held 40 together by means of the bolt 49 the side plates 52 will be clamped against the walls 44 and the lower portion of the shield member will be held in position by the ribs 53.

The lower part of each of the members 46 45 and 47 is bell-shaped as indicated at 54 to provide a hollow chamber for the sprocket 26 or any other sprockets which may be necessary. Each bell is provided with a substantially cylindrical shell 55 one portion of 50 which is broken away or notched as at 56 to provide room for the entry of the stand 29. The pivot pin 27 extends through hubs 57 and 58 formed, respectively, on the members 46 and 47, said pin being held in position by means of set screws 59. Certain portions of the cylindrical shells 55 abut each other so as to hold the substantially vertical webs 60 of the two bells in spaced relation. This construction is set forth clearly in Fig. 52 and is maintained by the set screws 59 which are set tightly against the pin 27.

By referring to Fig. 3 it will be seen that the right or upper end of the notch 56 as designated at 61 is spaced above the adjacent portion of the stand 29, and in like man-

ner the lower left end of the notch 62 is below the adjacent portion of the stand, thereby permitting the bells to move through a limited angular adjustment with respect to the stand 29.

It is believed that the manner of assembly 70 will be understood from the description already given, the shielding member 45 being first placed on its pivot pin and then the two elements 46 and 47 being fitted around opposite sides of the member 45. Each bell is slipped over its end of the pin 27, thereby rendering it unnecessary to remove the sprocket 26 from its operating position. The nut 50 and bolt 49 serve to clamp the 75 intermediate parts of the guard in fixed position and as previously described the set screws 59 will position the lower part of the guard.

I have shown a loom wherein the lay 80 extends somewhat beyond the vertical line passing through the pivot pin 27, but it not infrequently occurs that the lay will be of shorter length than that set forth herein, or it may be longer, in which case the same parts 85 of the guard as set forth can be employed but their relation with respect to each other will be somewhat different, the shielding member 45 moving down along the upright side plates 52 and also taking a different 90 angular position with respect to the lay when the latter is short, and a correspondingly 95 opposite relation will exist if the lay is longer than that shown in Fig. 1.

In certain other types of looms wherein 100 the lay is desired to be at a position somewhat higher with respect to the pivot pin 16 than that shown in Fig. 1, a similar adjustment will be made, the bolt 49 and nut 50 permitting an extension of the telescoping 105 members of the guard and the upper and lower members of the guard moving freely about their pivot pins 43 and 27, respectively. Where the guard is to be adapted to a loom requiring a considerable angular move- 110 ment of the bells from the position shown in Fig. 3 the ends 61 or 62, as the case may be, can be cut away so as not to interfere with the stand 29.

From the foregoing it will be seen that I 115 have provided a simple form of telescoping chain guard for a narrow ware loom wherein two parts are employed, one telescoping in the other, each part being supported for free pivotal movement about one of the already existing portions of the loom. It will be seen that a guard constructed as set forth herein can be used on a variety of narrow ware looms which have lays of different 120 lengths and also heights above the rocker 125 shaft 16. Furthermore, the means for pivotally supporting the lower portion of the guard also act as a mounting for the sprocket 26. Also, with certain types of narrow ware looms, the location of the rack rod 20 trans- 130

versely of the lay assumes different positions so that the chain and the upper sprocket 24 will assume different positions with respect to the front of the lay, and in order 5 to keep the guard central with respect to the chain an adjustment is made by means of the bolt 41 and slot 42 which extends transversely of the lay.

Having thus described my invention it will 10 be seen that changes and modifications may be made therein by those skilled in the art without departing from the spirit and scope of the invention and I do not wish to be limited to the details herein disclosed, but 15 what I claim is:

1. A guard for a narrow ware loom having 20 a lay and a rocker shaft between which extends a shuttle driving rack operating member, a pair of telescoping members, one pivotally mounted with respect to the lay, and the other pivotally mounted with respect to the rocker shaft and having portions to lie around the rack rod operating member.

2. A guard for a narrow ware loom having 25 a lay and a rocker shaft between which extends a shuttle driving rack operating member, a pair of telescoping members, one pivotally mounted with respect to the lay, and the other pivotally mounted with respect to the 30 rocker shaft and having portions to lie around the rack rod operating member, and clamping means to hold the members together.

3. A guard for a narrow ware loom having 35 a lay and a rocker shaft between which extends a rack operating member, a guard comprising upper and lower telescoping members, one member being pivotally mounted with respect to the lay, and the other member comprising two elements each pivotally mounted with respect to the rocker shaft and means to clamp said elements to the upper member.

4. A guard for a narrow ware loom having 45 a lay and a rocker shaft between which extends a rack operating member, a guard member pivotally mounted to the lay, a pair of guard elements one located on one side and the other located on the opposite side of 50 the member, a pivotal connection between said elements and the rocker shaft, and means to hold said member and elements together.

5. A guard for a narrow ware loom having 55 a lay and a rocker shaft between which extends a rack operating member, a guard member pivotally mounted to the lay, said member being substantially U-shaped in 60 horizontal cross section, and a pair of guard forming elements located on opposite sides of the member and having telescoping relation with respect to the latter, and clamping means to hold said elements against the member, the lower portion of the elements being

pivotaly mounted with respect to the rocker shaft.

6. In a guard for a narrow ware loom having 70 a lay and a rocker shaft with a sprocket supported with respect to the shaft and around which a rack operating chain extends, a pair of telescoping guard members, one pivotally mounted with respect to the lay and the other pivotally mounted around the axis of the sprocket.

7. In a guard for a narrow ware loom having 75 a lay and a rocker shaft with a sprocket supported with respect to the shaft and around which a rack operating chain extends, a pair of telescoping guard members, one pivotally mounted with respect to the lay, and the other pivotally mounted about the axis of the sprocket, said other having a bell shaped portion to receive the sprocket.

8. In a guard for a narrow ware loom having 80 a lay and a rocker shaft with a sprocket supported with respect to the shaft and around which a rack operating chain extends, a guard member pivotally mounted to the lay, and a pair of guard elements each pivotally mounted about the axis of the sprocket and having a bell-shaped portion, said portions being in alignment to define a chamber for 85 the sprocket, said member and pair of elements having telescoping relation, and means 90 to clamp the elements to the member.

9. In a guard for a narrow ware loom having 95 a lay and a rocker shaft with a sprocket supported with respect to the shaft and around which a rack operating chain extends, a pivot pin for the sprocket, a guard member pivoted to the lay, and a pair of guard elements each mounted on the pin for the sprocket and secured thereto, the member and elements having telescoping relation, and 100 means to clamp said elements and member together.

10. In a guard for a narrow ware loom having 105 a lay and a rocker shaft with a sprocket supported with respect to the shaft and around which a rack operating chain extends, a pivot pin for the sprocket, a guard member pivoted to the lay, and a pair of guard elements each mounted on the pin for the sprocket and secured thereto, the member and elements having telescoping relation, and 110 means to clamp said elements and member together, the elements having similar but 115 oppositely extending bell-shaped portions to receive the sprockets.

11. A guard for a narrow ware loom having 120 a lay and a rocker shaft between which extends a rack operating member, a pair of telescoping members, one pivotally mounted with respect to the lay, and the other pivotally mounted with respect to the rocker shaft and having portions to lie around the rack operating member, and means to vary the pivotal support for the upper member relatively 125 to the lay.

12. A guard for a narrow ware loom having a lay and a rocker shaft between which extends a rack operating member, a pair of telescoping guard members, one of which is pivotally supported with respect to the rocker shaft, a pivotal support for the other member mounted on the lay, and means to hold said pivotal support for the other member in any one of a plurality of positions relatively to the lay.
13. A guard for a narrow ware loom having a lay and a rocker shaft between which extends a rack operating member, a pair of telescoping guard members, one of which is pivotally supported with respect to the rocker shaft, a pivotal support for the other member mounted on the lay, and means to hold said pivotal support for the other member in any one of a plurality of positions relatively to the lay in a direction transverse of the lay.
14. A guard for a narrow ware loom having a lay and a rocker shaft between which extends a shuttle rack operating member, a pair of telescoping guard members, one of said members pivoted to the lay and having spaced parallel side walls between which extends an end wall to connect said side walls, ribs formed on the side walls spaced from and substantially parallel to the end wall, the second member being pivotally mounted with respect to the rocker shaft and being located between the end wall and ribs to be limited in pivotal movement by the ribs and end wall.

In testimony whereof I have hereunto affixed my signature.

ELBRIDGE R. HOLMES.
